CLAIM

The ornamental design for skin cover set for game console, as shown and described.

DESCRIPTION

FIG. 1 is an exploded view of the skin cover set for game console showing my new design;

FIG. 2 is a front elevational view thereof;

FIG. 3 is a rear elevational view thereof;

FIG. 4 is a perspective view thereof; showing the claimed design in condition of use; and,

FIG. 5 is another perspective view thereof.

The broken lines in the drawings show environmental structure of the skin cover set for game console that form no part of the claim.
